DESIGN FOR AN AUTOMATIC DOUGHNUT MACHINE

Ernest J. Roth, Rockleigh, N. J., assignor to Joe
Lowe Corporation, New York, N. Y., a corpora-
tion of Delaware

Application June 10, 1947, Serial No. 139,558

Term of patent 14 years

(Cl. D81—10)

To all whom it may concern:

Be it known that I, Ernest J. Roth, a citizen of the United States, residing at Rockleigh, in the county of Bergen and State of New Jersey, have intended a new, original, and ornamental Design for an Automatic Doughnut Machine, of which the following is a specification, reference being had to the accompanying drawings, forming part thereof, in which:

Figure 1 is a perspective view of an automatic doughnut machine, showing my new invention, looking from the right end thereof;

Figure 2 is another perspective view of the automatic machine shown in Figure 1, looking from the left end thereof; and

Figure 3 is a top plan view of the automatic doughnut machine shown in Figure 1.

The side, not shown, is substantially like the side shown.

What I claim is:

The ornamental design for an automatic doughnut machine, as shown and described.

ERNEST J. ROTH.
